UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 22,067, dated December 20, 1892.

Application filed November 22, 1892. Serial No. 452,885. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons and other Similar Articles, of which the following is a specification, reference being had to the accompanying drawing, forming a part thereof.

The figure is an upper or front face view of a spoon handle embodying my design.

The leading feature of my design is a special arrangement of the leaves and blossoms of the chrysanthemum applied to the handle of the spoon as follows. From the shank of the spoon to its outer end there is a gradually

widening and closely joined mass of leaves, buds and blossoms. At *a* and *a'* there appear buds among the leaves, and at the outer 20 end of the handle there is a full blown blossom or bloom *b* of the chrysanthemum. The outer edges of the leaves and bloom impart their irregular outline to the margin of the handle. 25

What I claim is—

The design for the handles of spoons and other similar articles as herein shown and described.

AUSTIN F. JACKSON.
